UNITED STATES PATENT OFFICE.

FRANK P. STONE, OF CHICAGO, ILLINOIS.

WEATHER-STRIP FOR SASHES OR SLIDING DOORS.

SPECIFICATION forming part of Letters Patent No. 366,524, dated July 12, 1887.

Application filed December 15, 1886. Serial No. 221,665. (No model.)

To all whom it may concern:

Be it known that I, FRANK P. STONE, of Chicago, in the county of Cook and State of Illinois, have invented certain new and useful 5 Improvements in Weather-Strips for Sashes or Sliding Doors, of which the following is a specification, reference being had to the accompanying drawings.

The object of my improvements is to provide a weather-strip which is particularly applicable to the sashes of car-windows, but may be applied to sashes generally, or to sliding doors, so as to close the openings between the sashes and window-frames on both sides of 15 the sashes—that is to say, on the outside and on the inside. This is particularly important in car-windows, where strong currents of air and much dust are liable to be driven through cracks around window-sashes into cars.

20 In the accompanying drawings, Figure 1 is an elevation, partly in section, of a window sash and frame with my improvements applied, and Fig. 2 is a cross-section of the same. Fig. 3 is a sectional detail showing a formal modification.

25 A indicates an ordinary car-window frame, and B an ordinary glazed sash. The sash is provided with a rubber or other suitable strip or packing, C, upon its opposite edges. This 30 strip, as illustrated, it will be seen, is between the edge of the sash and a wooden strip or slide, D, secured to the edge of the sash over the rubber in any suitable way, as by nails or screws. The slide D is preferably thinner 35 than the sash, and may be a part of the sash and projecting from it, and the rubber may be applied in two narrow strips on opposite sides of the slide D; but I prefer to use only one strip of rubber projecting a little outside and 40 inside, and a separate piece, D, as illustrated, because that is the quickest and cheapest way to embody this part of my improvements; but the slide D may be as thick as the sash, and the rubber C project slightly on each side, as 45 indicated in Fig. 3.

By reference to Fig. 2 it will be seen that

the window-frame is made with a recess in section corresponding to the section of the sash—that is to say, I provide a wide groove, E, with a narrow groove, F, in its bottom, 50 so as to leave shoulders G. The rubber packing fills the wide groove and bears on either side of it lightly, so as to close the opening effectually on both sides between the sash and its frame. The strip D enters the narrow 55 groove and is provided with springs H, preferably anti-rattling sash-springs, such as shown in my United States Patent No. 263,240. These springs form the principal bearings of the sash upon the frame, and so make it unnecessary for 60 the rubber strip to press very hard upon the frame. Thus the main wear of sliding the sash will be upon the springs, which are enduring, and the rubber may be so fitted as to cause the minimum friction consistent with tightly 65 packing the joints. The rubber will of course contract and expand slightly on either side to accommodate the shrinking and swelling of the sash and frame, so as always to preserve tight joints on the outside and inside of a window, and thus very effectively exclude dust. 70 The tops and bottoms of the sash may be protected in any ordinary way against the admission of dust.

What I claim to be new, and desire to secure 75 by Letters Patent of the United States, is—

1. The combination, with the sash, of the strip D, the rubber packing interposed between the sash and strip and projecting from both sides thereof, and the anti-sash-rattling 80 springs H, substantially as set forth.

2. The combination, with the sash, of a rubber packing projecting from both sides, a strip, D, and a frame provided with a wide and narrow groove, and shoulders to fit the 85 sash and strip D, substantially as set forth.

In testimony whereof I have hereunto subscribed my name.

FRANK P. STONE.
